UNITED STATES PATENT OFFICE.

FRED T. MADSEN, OF FOREST PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TESTING EQUIPMENT FOR AUTOMATIC TELEPHONE SYSTEMS.

Application filed October 15, 1924, Serial No. 743,660. Renewed May 28, 1927.

This invention relates in general to testing equipment for automatic telephone systems, but is concerned more particularly with the testing of systems wherein telephone numbers are registered, translated and retransmitted by devices common to a number of trunks. In such a system a trunk switch, seized by the calling subscriber, seizes a translating device. Relays in the trunk switch repeat the impulses from the subscriber's calling device to the mechanisms of the translating device seized. The device translates and retransmits the number over a trunk leading to a train of automatic switches. The translated number may contain either fewer, the same, or more digits than the original number, and the digits themselves may be of fewer or more impulses.

20 This invention relates specifically to the testing of the trunk switch and translating device. I have chosen the so-called director system including the director selector to illustrate my invention, although it is equally well adapted to test any device performing the same functions.

One of the objects of this invention is to test the trunk circuit relays of the director selector to determine if they are in correct adjustment. This is accomplished by impulsive the relays by means of a standard calling device or a varying machine, and by extending the impulse circuit so that impulses delivered by the relays operate standard switch mechanisms on the test set.

40 The varying machine is arranged to impulse relays controlling a switch mechanism at a definite rate of speed over a high resistance loop, and to again impulse the relays over a short loop which is shunted by a low resistance corresponding to a leaky line.

Another object is to test the switch-through function of the director selector. Switch-through occurs when the director has finished transmitting the digits of the telephone number, and serves to disconnect the director from the trunk and to connect the two ends of the trunk together.

50 Still another object of this invention is to apply the above varying test to the switch mechanism of the director. The varying machine impulses a set of standard relays on the test set which are set in proper adjust-

ment, and the switch mechanisms of the director are adjusted to operate on impulses from these relays.

A further object is to determine if the impulses sent out by the director are of the proper ratio of make and break, and if they are sent out at the correct speed.

Another object of this invention is to determine if the director sends out the proper digits. A certain number is dialled into the director and the translated number which the director sends out is intercepted and recorded on the test set register, so that its accuracy may be checked.

A still further object is to provide a circuit arrangement whereby the impulse relays and the switch mechanisms of the test set itself may be checked to determine if they are in proper adjustment.

There are several other objects and features of this invention which can be understood best from a perusal of the detailed description which is to follow.

Referring to the drawings, Figs. 1 and 2 show the circuit arrangements of the test set proper.

Fig. 3 shows the circuit arrangement of the trunk circuits, director selector, and director.

Fig. 4 shows the structure of the register mechanisms 115-134, inclusive, of Fig. 2.

Fig. 5 shows a sectional view of indicator hub assembly of the register shown in Fig. 4, taken along the line A—A in the direction of the arrows.

The director is shown in Fig. 3 only in part for the reason that it is well known, reference being made to the application of Martin L. Nelson, Serial No. 719,459, filed June 12, 1924. The director is not a part of the present invention, and is not disclosed because it has been explained in detail in the above application.

Two sets of test jacks J^3 and J^4 , and J^1 and J^2 are shown in Fig. 3. The former set is located on the director selector board in one of the trunks leading to the directors. Each director is equipped with a pair of jacks such as J^1 and J^2 for purposes which will be hereinafter explained.

Referring to Fig. 1, twin test plugs P^1 and P^2 are arranged to be in circuit in either J^1 and J^2 or J^3 and J^4 . Test plugs TP^1 and

TP² are arranged to be inserted in either TJ¹ of Fig. 3, or TJ² of Fig. 1. Test plug TP² is connected to the testing mechanism 80 which is shown only in part. This mechanism is the well known varying machine which is explained in detail in the Patent No. 1,523,036 issued to H. F. Obergfell, on Jan. 15, 1925.

The manual keys 2-13, inclusive, control the circuit from these test plugs to the relays 15-19, inclusive, while the calling device 1, which is of the well known type, is operated to send impulses to the director selector.

Referring again to Fig. 1, the impulse recording mechanism 79 may be any one of a number of well known impulse recording mechanisms, such as a printing telegraph device for example.

Referring to Fig. 2, relays 101-104, inclusive, are the control relays for the switch mechanisms 168 and 169. These mechanisms are of the well known type in which the primary movement steps the shaft up off a row of contacts or levels, and the secondary movement steps the shaft and wipers around to a contact in that level. Magnets 113 and 114 control the wiper 170 of the register control switch RC, thereby controlling the registers 115-124, inclusive. Release of the registers is accomplished by means of release key 172 which energizes the series parallel arrangement of release magnets 125-134, inclusive.

Referring to Fig. 4, the register mechanism consists of the bracket 500 upon which are mounted the magnets 115 and 125, which operate the armatures 501, 503, to control the indicator 507. Magnet 115 attracts armature 501 which moves pawl 502 into engagement with ratchet 505 to step the indicating arm 507 in a clockwise direction. Armature 503 forms a detent which engages the ratchet 505 to hold the indicating arm in its set position. The figures on the indicator are visible through the window 509 of the front plate 508.

Magnet 125 is energized to release the register. It attracts armature 503, withdrawing the detent from the ratchet, freeing the indicator arm which falls to its normal position against stop 510.

Fig. 5 is a section view of the hub assembly of the indicator 507 of Fig. 4. The ratchet 505 is extended forming a bearing around shaft 515. Assembled on the ratchet hub are the stop lever 511, spacing washer 512, indicator mounting bracket 506, and spacing washer 513. The assembly is locked together by nut 514 and held on the shaft 515 by the collar 504.

To execute one of the objects of this invention, that is, the varying of the director selector trunk relay, the attendant inserts TP² of the testing equipment into TJ¹ of the trunk circuit relays of the director

selector. He then sets the wipers 441-444, inclusive, onto the trunk set aside for testing purposes, that trunk being the one which contains the jacks J³ and J⁴. He then inserts plugs P¹ and P² of the test set into jacks J³ and J⁴, respectively, of the director selector trunks, completing a circuit from the test set into the director selector and back into the test set. He then operates key 7 of the test set to arrange the circuit so that the impulses sent out by the testing mechanism 80 are sent in to the pulsing relay 421 of the trunk circuit. The impulses sent by this relay are brought in through the test circuit to operate switch mechanisms 168 or 169, thereby enabling the operator to tell when he has the trunk circuit relay 421 properly adjusted.

When the attendant has completed his varying test of the trunk circuit relay, he removes test plug TP² from the test jack TJ¹ and inserts in its place test plug TP¹. He then restores key 7 to normal and operates the key 8, arranging the circuits to complete the circuit of relay 423. This relay functions to switch through the trunk circuit relays of the director selector and to disconnect the director from the trunk, and in so doing causes the test circuit to intermittently light the lamp 84, giving the attendant an indication that the switch-through is completed.

It is necessary that the switch mechanism and registers of the director be kept in adjustment so that they will function properly with the trunk circuit relay 421. To check up on this adjustment the attendant inserts twin plugs P¹ and P² in J¹ and J² of the director and inserts TP² of the varying machine into the test jack TJ² of the test set. He then restores key 7 to normal and operates key 8, thereby arranging the circuit so that the impulses sent out by the varying machine will operate the standardly adjusted relay 102 of the test mechanism, which relay impulses the switch mechanism and registers of the director in their proper order. After having the mechanism properly adjusted, the attendant restores key 8 and operates key 10 to position A and key 12 which arranges the circuit so that the director impulses directly into the impulse recording mechanism 79, permitting a check on the ratio and speed of the impulses sent out by the director. The attendant then restores the keys 10 and 12 and reoperates key 10 to position A and operates key 5 to connect the calling device 1 in circuit with the test set talking relay 102. He then dials the number into the register mechanism of the director, which number is translated and sent out over the line circuit of the director to operate the pulsing relay 101 of the test set. This relay operates the test set registers 115-124, inclusive, recording thereon the number ac-

tually sent by the director. When the director has finished sending this translated number it cuts itself out automatically, thereby lighting the signal 84 to notify the attendant that it has finished with its operation. The attendant may then read the number sent directly on the registers of the test set, and if they are correct release the registers by operation of release key 172, and release the director by restoring the key 10.

It is easily seen that the standard pulsing relay and switch mechanisms of the test set, by means of which the testing relay of the director selector and switch mechanisms of the director are adjusted, must be rousted frequently to see that they are kept in proper adjustment. This is accomplished by inserting the test plug of the varying machine TP^2 into TJ^2 and operating key 10 to position A and key 6 and key 9 to position A. The circuits are then arranged so that the standard pulsing relay 101 will send impulses to the switch mechanism 168. By restoring key 9 to normal and operating key 11 to position A, the impulses from this pulsing relay 101 will be sent to switch mechanism 169. By restoring the key 6 to normal, the attendant disconnects pulsing relay 101 and connects in its place relay 102 which he then tests in a similar manner. By operating key 13 the attendant may send the impulses sent out by relay 102 to the impulse recording mechanism, thereby checking them for impulse ratio and speed.

Having thus explained my invention in general, I will now explain its operation in detail. To test the director selector for pulsing the attendant inserts the test plug TP^1 into the test jack TJ^1 closing a circuit of trunk circuit relay 421 which may be traced from ground through the lower winding of relay 421, spring 433 and its break contact, conductor 417, contact 491 of the test jack TJ^1 , lower line conductor of the test plug TP^1 , conductor 64, spring 21 and its normal contact, conductor 82, main spring 3^A and its normal contact, conductor 71 to the impulse springs of the calling device 1, conductor 72, through the normally closed contacts of key 4, to spring 20 and its normal contact, through conductor 63, the upper line terminal of test plug TP^1 , conductor 490 of the test jack TJ^1 , to conductor 415 through spring 430 and its break contact, to the upper coil of relay 421, to battery to ground. Relay 421 energizes over the above circuit and at spring 425 closes the circuit to relay 422 which may be traced from ground through relay 422, main spring 425 and its make contact, resistance 424, battery to ground. Relay 422 energizes and at its main spring 426 and make contact places a ground on the release trunk conductor 416, thereby preventing a line switch from seizing this director selector. The at-

tendant then manually moves wipers 441-444, inclusive, until they are in connection with the test trunks 494-497 inclusive, respectively. As this test trunk is idle at the time, there will be no ground potential on bank contact 443, and the circuit to 435 will be completed from ground to make spring 428, relay 435, armature spring and break contact of magnet 440 through magnet 440 to battery to ground. Relay 435 energizes and closes its make contacts 436-439, inclusive, extending the trunk conductors 445 and 448 to the loop of the director. The magnet 440 does not energize in series with the high resistance relay 435. Twin test plugs P^1 and P^2 are then inserted in test jacks J^3 and J^4 , thereby connecting the impulsive circuit of the director selector trunk relay to the test set mechanism. Key 7 is operated to open the circuit of the release magnet of mechanisms 168 and 169. The calling device 1 is then operated to alternately open and close the circuit of relay 421, thereby causing relay 421 to impulse. When relay 421 falls back, it opens the circuit of relay 422 and immediately applies a short circuit through the winding thereof, which holds relay 422 in an energized position for a short time. Relay 421 also closes the circuit from ground at the break contact of relay 421, through the make contact 427, through the make contact 439, through wiper 444 and its associated test trunk conductor 497, through the ring contact of jack J^4 and test plug P^2 through main spring 11^B and its break contact, through main spring 9^B and its break contact, over conductor 81, through the break contact of spring 42 to spring 38 and its break contact, over conductor 54, through off normal switch spring 156 and its break contact, through relay 106, to vertical magnet 105 to battery to ground. Relay 106 and vertical magnet 105 energize over the above traced circuit. Magnet 105 advances the shaft one step, closing off normal springs 157 so that the remaining impulses go through spring 156 and its make contact, spring 159 and its make contact, through relay 106, magnet 105 to battery. Relay 106, being slow to release, remains in an operated position during the impulses. At the end of the series of impulses relay 106 de-energizes, changing the circuit at spring 159 so that the next train of impulses will operate rotary magnet 108 instead of vertical magnet 105.

The switch mechanism 168 may then be released by the operation of key 2, which closes a circuit from ground at make contact of key 2, over conductor 85, make contact of the off normal switch 157, magnet 107 to battery. Magnet 107 operates to release the switch mechanism, which, upon returning to normal, opens the off normal switch contacts 167 thereby opening the cir-

cuit to magnet 107. By the operation of key 3 to position A the attendant may connect series resistance 69 in series with the loop of relay 421, with the result that relay 5 421 will deliver a heavy impulse to the switch mechanism 168. Switch mechanism 168 is maintained in adjustment so that it will fail on impulses which are heavier than the degree of heaviness set as one of the 10 limits beyond which impulses must be regulated to operate satisfactorily under varying line conditions. If, with resistance 69 in series with the loop, relay 421 delivers impulses which are not heavy enough to 15 make switch mechanism 168 fail, the tension of the springs of relay 421 is varied until the impulses are heavy enough to make switch 168 fail.

By throwing key 3 to position B, the 20 attendant may throw shunt resistance 70 across the loop in parallel with the impulse springs of the calling device, thereby causing impulsive relay 421 to deliver a light impulse. By operating key 9 to position B 25 the impulse circuit of mechanism 168 is opened, and the impulse circuit from relay 421 is closed to the magnets of mechanism 169. This circuit is the same up to the ring conductor of P², from whence it goes 30 to spring 11^b and its break contact, spring 9^b and its make contact, conductor 56, off normal switch spring 154 and its break contact, relay 110, and magnet 109 to battery to ground. The operation of mechanism 35 169 is identical with that of mechanism 168 except for the fact that mechanism 169 is maintained in such adjustment that it will fail on impulses which are lighter than the degree of lightness set as the other limit 40 beyond which the impulses must be regulated to operate satisfactorily under varying line conditions. If, with resistance 70 in shunt of the impulse springs, relay 421 transmits impulses which are not light 45 enough to cause switch 169 to fail, the springs of relay 421 are adjusted until the impulses are light enough to cause that switch to fail.

The impulses are then diverted to first 50 one, then the other of switch 168 and 169 by the operation of key 9 and the adjustment of springs of relay 421 varied until the impulses are so regulated that they will be heavy enough with resistance 69 in series 55 with the loop to cause switch 168 to fail and light enough with resistance 70 in shunt of the impulse springs to cause switch 169 to fail.

Mechanism 169 may then be released by 60 operation of key 2, which closes a circuit from ground to the make springs of key 2, conductor 85, conductor 149, off normal spring 155 and its make contact, magnet 112 to ground to battery. Magnet 112 operates 65 to release the mechanism, which upon re-

turning to normal opens the off normal switch spring 155.

Having completed the adjustment of relay 421 the attendant may then test the director selector switch-through by restoring keys 3 and 9 to normal, and operating key 8. The operation of key 8 closes the circuit of relay 461, which is traced from ground to the lower winding of relay 461, conductor 448, spring 433 and the break 70 contact, main spring 437 and its make contact, wiper 442 and its associated test trunk conductor 495, the ring of jack J³ and test plug P¹, spring 32 and its break contact, conductor 66, spring 26 and its make contact, conductor 75, through the lower winding of relay 17 to conductor 73, spring 33 and its break contact, to the tip of plug P¹ and jack J³, conductor 494, wiper 441, make contact 436, conductor 445 to the upper coil 80 of relay 461 to battery to ground. Relay 461 and relay 17 energize over the above circuit.

Relay 17, upon energizing, closes a circuit from ground through make contact 43 90 to the coil of relay 16 to battery to ground. Relay 16 energizes and closes the circuit from ground through the make contact of spring 25, through spring 42 and its make contact, conductor 81, to the break contact 95 of spring 9^b, to the break contact of spring 11^b, to the ring conductor of the test plug P² and the test jack J⁴, conductor 497, wiper 444, make contact 439, make contact 427, make contact of relay 421, to relay 423 to 100 battery to ground. Relay 17, upon energizing, also closes a circuit from ground through make contact 83 through signal 84 to battery, lighting the signal 84.

Relay 423, upon energizing, opens the 105 previously defined paths of relays 421 and 461, switching through test jack conductors 415 and 417 directly to the relay 461 and opening the circuit just described for relay 17. Relay 17 falls back immediately extinguishing lamp 84. The momentary flash 110 of the signal 84 notifies the attendant that the switch-through was successfully accomplished.

It is necessary to frequently vary relay 115 421 with the standard varying machine 80. To do this the attendant removes the test plug TP¹ from the test jack TJ¹ and inserts in its place test plug TP², thereby connecting the varying machine 80 through the 120 pulsing relay 421 of the trunk circuit. By manipulation of the keys K, K¹ and K² of the varying machine 80, the attendant may operate the relay 421 over a long loop and over a shunted line. The details of the operation of the varying machine 80 are well known, being disclosed in full in the Patent 1,523,036 granted to Herbert F. Obergfell, on Jan. 13, 1925. The impulses set up by 125 relay 421 are conducted over the above de- 130

scribed circuit to operate switch mechanisms 168 and 169 of the test set.

If, for any reason, the attendant desires to know exactly what kind of an impulse

- 5 the pulsing relay 421 is delivering he can, by operating key 11 to the B position, divert those impulses to the impulse recording mechanism 79, over the circuit traceable from ground to the break contact and relay 10 421, make spring 427, spring 439 and its make contact, wiper 444 and its associated test trunk conductor 497, through the ring of jack J¹ and plug P², main spring 11^B and its make contact, conductor 78, through the 15 impulse recording mechanism 79 to ground-ed battery. The operation of key 11 also closes a circuit from ground through spring 31 and its make contact, conductor 77 to mechanism 79. This ground starts the 20 mechanism preparatory to recording the impulses received on conductor 78.

When the directors are to be tested, it is necessary that they be temporarily put out of commission and made busy so that the 25 director selectors cannot seize them. This is accomplished by operating locking key P which places ground on the private conductor 481 through the break contacts of jack J¹ to conductor 496, through the banks 30 of the director selector, over which wiper 443 rotates. The presence of ground on this bank contact prevents any director selector from stopping on the contact. The attendant then blocks the dead code relay 35 902 in a normal position to prevent the director from sending the dead code number in case such a code is called during the director test. This relay is not shown in Fig. 3, but is shown in detail and explained 40 in the application of Martin L. Nelson, Serial No. 719,459, filed June 12, 1924. The attendant then plugs relay 810 in its operated position, thereby opening the circuit to the 45 sender control switch of the director, which switch is not shown in this drawing but is explained in the above application. Twin 50 test plugs P¹ and P² are next inserted in the director test jacks J¹ and J², and manual key 10 of the test set operated to its A position with all the other keys restored to normal. The circuit is then closed from 55 ground, spring 28 and its make contact, the tip of plug P² and jack J², through relay 806 to battery. Relay 806 energizes and at spring 837 and make contact closes the circuit from ground through relays 811 and 810 in series to battery. Relay 810 does not energize in series with the high resistance of relay 811. Relay 811, upon energizing, shunts itself out at spring 812 and its make contact, and, after an interval, falls back, breaking contact of spring 812 and opening the impulsing spring 813. When 60 relay 811 is shunted out, 810 energizes to

control the sender switch as explained in the 65 above application. This operation continues at a definite rate of speed as long as spring 837 maintains the circuit closed.

The operation of key 10 to position A also closes a circuit from ground through spring 70 27 and its make contact, conductor 76 to relay 15 to battery and ground. Relay 15 energizes over this circuit and prepares the impulsing circuit, which will be explained 75 hereafter. The impulsing of the loop by spring 813 is without effect at this time because of the short held on the loop by spring 854 and its break contacts, which are in multiple with spring 813.

To vary the switch mechanisms and registers of the director, the attendant inserts the test plug TP² into TJ² of the test set, closing the circuit from ground through the lower winding of relay 102, conductor 49, spring 23 and its break contact, conductor 80 85 67 through the test jack and plug to conductor 60, through the varying machine 80, conductor 61, through the test plug and jack to conductor 68, spring 22 and its break contact, conductor 47 to the upper coil of relay 90 102 to battery and ground. Relay 102 energizes and closes a circuit from grounded battery to resistance 171, spring 162 and its make contact to relay 104. Relay 104 energizes and further prepares the impulsing 95 circuit. By manipulation of keys K¹ and K² of the varying machine 80, the attendant may impulse relay 102 with either a light or heavy impulse. When relay 102 falls back during the impulsing, it closes a circuit from ground through spring 162 and its break contact, spring 160 and its make contact, conductor 59, spring 35 and its break contact, conductor 65, spring 40 and its make contact, conductor 81, spring 9^B 100 and its break contact, spring 11^B and its break contact, through the ring P² and the jack J², conductor 452, through relay 702, wiper arm 719 and its first contact, to magnet 909 to battery to ground. Relay 702 105 energizes over the above circuit and remains in an energized position during the impulsing, because of the slug on the heel end of the core. Magnet 909 energizes and falls back with the impulses, stepping up the 110 switch mechanism one step for each impulse. When relay 102 falls back the circuit of relay 104 is opened and short circuited at spring 162 and its break contact. However, relay 104 is adjusted to remain in an energized position during the impulsing, being held up by its short circuited winding. As 115 relay 102 is falling back a circuit is momentarily closed from ground through spring 162 and its break contact, spring 161 and its make contact, conductor 52, spring 41 and its make contact, through the upper winding of relay 17 to battery to ground. How-

ever, relay 17 is so adjusted that it does not respond to such short impulses and remains deenergized.

At the end of the first series of impulses, 5 relay 702 deenergizes and closes circuits which move the wiper 719 from a first to a second position, thereby preparing a circuit to magnet 910 so that the second set of impulses operates the latter magnet to rotate 10 the switch mechanism of the director. These circuits are not shown in Fig. 3, but are explained in detail in the above application. The magnets of the digit register are each operated in turn over the circuit closed 15 by wiper 719 which is controlled in the manner just described.

To release the switch mechanisms and registers of the director, the attendant restores key 10 to its normal position which 20 releases the relay 806 and restores the director in the manner explained in detail in the reference of record. The attendant repeats the impulsing and release operation on 25 light and heavy impulses from the varying machine until the switch mechanism and registers of the director are found to be in proper adjustment.

To test the impulses sent out by the impulsing spring 813 of the director, the attendant operates key 10 to position B closing 30 a circuit from ground through spring 30 and its make contact, the sleeve conductor of plug P² and jack J², conductor 863, to the director start relay which is not shown. 35 This start relay operates to remove the short circuit from the loop at spring 854 and its break contact. The operation of key 10 also closes a circuit from ground through spring 29 and its make contact, the tip of plug P² 40 and jack J² to relay 806 to battery, energizing relay 806 to start impulsing relay 811 as previously explained. The operation of key 12 closes a circuit from the impulse recording mechanism 79 over conductor 77, 45 spring 32 and its make contact, the ring of plug P¹ and jack J¹, conductor 450, through the impulsing spring 813, conductor 449, to the tip of jack J¹ and plug P¹, spring 33 and its make contact, conductor 78 to the impulse recording mechanism. Springs 813 50 impulsive this circuit continuously. The impulses may be studied from the record of mechanism 79.

To test the director for sending the proper 55 digits, the attendant operates key 10 to position A and operates key 5 with all other keys normal. Relay 15 energizes upon the operation of key 10 as has already been explained. Relay 15, upon energizing, closes 60 the circuit of relay 101, which may be traced from ground, through the upper winding of relay 101, conductor 51, spring 37 and its break contact, conductor 73, spring 33 and its make contact, the tip of plug P¹ and jack J¹, conductor 449, impulsing springs 813, 65

conductor 450, through the ring of jack J¹ and plug P¹, to spring 32 and its break contact, conductor 66, spring 36 and its make contact, conductor 46, through the lower winding of relay 101 to battery. Relay 101 70 energizes and at spring 166 and its make contact closes a circuit from ground through the winding of relay 103 to battery, and at spring 163 opens the impulse circuit. Relay 103 energizes and at spring 164 prepares the 75 impulse circuit which will be explained later. The operation of key 5 closes a circuit from ground through the lower winding of relay 102, conductor 49, spring 23 and its break contact, spring 20 and its make 80 contact, normally closed contact to key 4, conductor 72, through the impulse control springs of the calling device 1, conductor 71, through the break contacts of key 3^A, conductor 82, through spring 21 and its make 85 contact, through spring 22 and its break contact, conductor 47, through the upper coil of relay 102, to negative battery to ground. Relay 102 energizes and closes the 90 circuit to relay 104, as has been previously described. When the calling device 1 is operated impulse springs open and close the circuit of relay 102 causing it to impulse over the impulse circuit to the director, as 95 has also been previously described. By manipulation of the calling device the attendant is able to set up a telephone number on the registers of the director, which translates the number and at the proper time starts 100 impulsing the above traced circuit to relay 101. Relay 101 falls back with each impulse and closes the circuit from ground to spring 39 and its make contact, spring 24 and its break contact, conductor 50, spring 163 and its break contact, spring 164 and its make 105 contact, conductor 55, spring 9^A and its break contact, spring 11^A and its break contact, through relay 18 to battery to ground, and also over conductor 67, wiper 170, conductor 137, magnet 115 to battery. Relay 18 110 energizes over the above circuit and remains in an operated position throughout the impulsing because of the slug on the heel end of the core. Magnet 115 follows the impulsing, advancing its register in accordance 115 with the first digit sent out by the director. When relay 101 falls back, it also opens the circuit of relay 103 at springs 166. However, relay 103 is a slow to release relay and remains in operated position during the 120 impulsing.

Relay 18, upon energizing, closes a circuit, ground through spring 44 and its make contact, through the coil of relay 19 to battery. Relay 19 energizes and at spring 45 prepares the circuit to the register control magnet 113. The circuit, however, is held open at spring 44 by relay 18. When the director has finished sending the first digit of the translated telephone number, spring 856 130

closes with its make contact and shunts out the impulsing springs 813 as is explained in the application of reference. Relay 101 comes to rest energized, and at 163 opens the circuit of relay 18 which falls back after a brief interval, opening the circuit of relay 19 and closing the circuit from ground through spring 44 and its break contact, spring 45 and its make contact, conductor 58, through magnet 113 to battery. Magnet 113 energizes and advances the wipers 170 to the second contact in connection with conductor 138 and magnet 116. Relay 19, which remained operated for a brief time after its circuit was opened because of the copper slug on the heel end of the core, finally falls back and at spring 45 opens the circuit just traced to magnet 113. The second digit sent out by the director is therefore registered on the second register by magnet 116, the performance being the same as just described.

When the director has finished sending the last digit it cuts itself off and restores to normal in the well known manner, places a ground on the impulse wire which closes the circuit from ground on conductor 452 through the ring of jack J^2 and plug P^2 , spring 11^B and its break contact, spring 9^B and its break contact, conductor 81, spring 40 and its make contact, conductor 65, spring 35 and its break contact, conductor 59, spring 160 and its make contact, spring 161 and its make contact, conductor 52, spring 41 and its make contact, through the upper winding of relay 17 to battery. Relay 17 energizes and at spring 43 closes a circuit through the winding of relay 16 which energizes without effect at this time. Relay 17 also closes a circuit through spring 83 and its make contact, to the signal lamp 84, causing this lamp to light steadily, to notify the attendant that the director has cut through.

The number which the director has sent out is now registered on the test set registers 115-124, inclusive, and may be read directly off of these registers. To release these registers the attendant operates key 172 which closes a circuit from ground, through the make contact of key 172, conductor 136, to register release magnets 125 and 126 to battery, also to relays 127 and 128 in series to battery, and so on through the series parallel arrangement of the register release magnets. The director is released by restoring the key 10 to normal. Key 10 at spring 27 interrupts the previously described circuit for relay 15, which falls back, and at springs 36 and 37 interrupts the previously traced circuit for relay 101. Relay 101 restores and at spring 166 opens the circuit of relay 103 which restores after a brief interval, and at springs 167 and 164 prepares the release circuit for the release

magnet 114 of the register control RC. The register control is then restored to normal by operating the dial release key 4 which opens the previously traced circuit of relay 102, which falls back closing the circuit traceable from ground, through spring 162 and its break contact, through spring 160 and its break contact, relay 104 having fallen back when its circuit was opened at relay 162 as previously explained, conductor 53, through spring 39 and its break contact, through spring 24 and its break contact, over conductor 50, through spring 163 and its break contact, through spring 164 and its break contact, through springs 167, over conductor 148, through springs 165, through the winding of release magnet 114 to grounded negative battery. The registers and register control of the testing equipment and the registers of the director are then all returned to normal, ready to check the next number which is set up by the calling device in the foregoing manner.

The pulsing relay 102 and the switch mechanisms 168 and 169 of the test set are used as standards against which the pulsing relays and mechanisms of the director selector and director are checked. It is therefore necessary that these pieces of testing equipment should be frequently tested to make sure that their adjustment is standard. For this purpose I have provided circuit arrangements enabling the attendant to apply the standard routine test to his testing equipment.

To vary the pulsing relay 101 of the testing equipment, the attendant inserts TP^2 into test jack TJ^2 and operates keys 6 and 10 to position A and key 9 to position A. Circuits are then completed from ground through spring 27 and its make contact, conductor 76, through the coil of relay 15 to grounded battery. Relay 15 operates and prepares the impulsing circuit which will be hereinafter explained. A circuit is also closed from ground to the upper winding of relay 101, conductor 51, spring 23 and its make contact, conductor 67, through the test jack and plug to conductor 60, through the varying machine 80 to conductor 61, through the test plug and jack to conductor 68, spring 22 and its make contact, conductor 48, through the lower winding of relay 101 to battery. By manipulation of the keys K^1 and K^2 of the varying machine 80, pulsing relay 101 can be made to pulse with light or heavy impulses. The pulsing circuit of relay 101 may be traced from ground through spring 39 and its make contact, spring 24 and its break contact, conductor 50, spring 163 and its break contact, spring 164 and its make contact, conductor 55, spring 9^A and its make contact, spring 38 and its make contact, conductor 54, spring 156 and its break contact, through relay 106.

and magnet 105 to battery. Relay 101 pulsing over the above circuit operates mechanism 168 in the well known manner explained hereinbefore. To impulse the mechanism 169, the attendant restores key 10 to normal thereby releasing relay 15 which restores, and operates key 11 to position A. The impulsing circuit of relay 101 is then traced from ground to spring 162 and its break contact, spring 160 and its break contact, conductor 53, spring 39 and its break contact, spring 24 and its break contact, conductor 50, spring 163 and its break contact, 164 and its make contact, conductor 55, spring 9^A and its break contact, spring 11^A and its make contact, conductor 56, spring 154 and its break contact, to relay 110 and magnet 109 to battery to ground. Switch mechanism 169 then operates in the well known manner.

To test the impulses from the impulse relay 102, the attendant restores key 6 to normal, thereby connecting the relay to the varying machine 80 over a circuit which has been previously traced; and by operating key 13 diverts the impulses into the impulse recording mechanism 79 over a circuit which may be traced from ground through spring 162 and its break contact, spring 160 and its make contact, conductor 59, spring 35 and its make contact, conductor 78, to grounded battery in the impulse recording mechanism 79.

To test the digit registers 115-124, inclusive, the attendant connects the pulsing relay 101 to the varying machine in the manner just described, restores key 9 and key 11 to normal, operates key 10 to position A to close the previously described circuit to relay 15 thereby completing the pulsing circuit of relay 101 which may now be traced from ground through make contact 39, to break contact of key 7, conductor 50, spring 163 and its break contact, spring 164 and its make contact, conductor 55, spring 9^A and its break contact, spring 86 and its break contact, through relay 18 to ground and battery, and also over conductor 57 through wiper 170 and its first contact, conductor 137, through magnet 115 to battery. Relays 18 and 19 and magnet 115 function in the manner previously described to set up the registers 115-124, inclusive, in order from the impulses of relay 101.

Having described my invention, what I consider new and desire to have protected by Letters Patent will be pointed out in the appended claims.

What is claimed is:

1. In a telephone exchange, a plurality of trunk circuits containing relays, a plurality of digit translating devices common to said trunk circuits, a testing mechanism, means for connecting said testing mechanism to

said trunk circuits, means for connecting 65 said trunk circuits with one of said translating devices, and means for disconnecting the connected translating device and substituting the test mechanism therefor.

2. In a telephone exchange, a plurality of 70 trunk circuits containing relays, a plurality of translating devices common to said trunk circuits, means for associating one of said devices with a trunk circuit, testing mechanism, means for associating said test mechanism with the input and output circuits of 75 said trunk circuits and for dissociating said translating device therefrom, means in said test mechanism for transmitting impulses to the relays of said trunk circuit under varying 80 conditions, and means in the test mechanism responsive to impulses of direct current transmitted by said trunk circuit relays.

3. In a telephone exchange, a plurality 85 of trunk circuits containing relays, a test mechanism containing two switch mechanisms, one adjusted to operate on a light impulse, the other adjusted to operate on a heavy impulse, means for associating said test set with said trunk circuit relays and for 90 impulsing said relays, means for directing the impulses delivered by said relays to operate one of said switch mechanisms, and means for disconnecting said switch mechanism and for directing the impulses to the 95 other said switch mechanism.

4. In a telephone exchange, a plurality of 100 digit translating devices common to and controlled by a plurality of trunk circuits containing relays, a test mechanism, means for connecting said test mechanism to said translating device in lieu of said trunk circuits, and means in said test mechanism for then controlling said translating device.

5. In a telephone exchange, a plurality of 105 translating devices, said devices having means for registering a telephone number, translating it into fewer or more digits and retransmitting the translated number, a test mechanism containing relays and registers, 110 means for associating said test mechanism with one of said translating devices, means for causing said test mechanism relays to impulse into said translating device, and means for causing the translated telephone 115 number sent out by said translating device to be intercepted and registered upon said test mechanism registers.

6. In a telephone exchange, a plurality of 120 translating devices containing switch mechanisms, a test mechanism containing relays, means for connecting said test mechanism to one of said translating devices so that impulses delivered by one of said test mechanism 125 relays directly controls the switch mechanisms of said translating device, and means for operating said test mechanism relays under varying conditions.

7. In a telephone exchange, a plurality of translating devices arranged to register, translate and retransmit a telephone number and containing an impulsing device, a test mechanism containing a plurality of digit registers associated with a control switch, means for connecting said test mechanism to any one of said translating devices, said test mechanism comprising a relay responsive to the impulses of a digit sent by said impulsing device for actuating one of said registers, and means acting at the end of said digit for moving said control switch to associate said relay with the next register, said relay thereafter operating that register responsive to the impulses of the next digit sent by the impulsing device. 70
8. In a telephone exchange, a trunk circuit containing relays, a translating device associated with said trunk circuit, said translating device containing switch mechanism controlled by said trunk circuit relays, a test mechanism containing relays and a plurality of switch mechanisms, means for connecting said test mechanism with either said trunk circuit or the translating device, means in the test mechanism for impulsing either said trunk circuit or test mechanism relay, means in the one instance for directing the impulses delivered by the trunk circuit relays to their test set switch mechanisms, and means in another instance for directing the impulses delivered by said test set relays to cause them to operate either said test switch mechanism or said translating device switch mechanism. 85
9. In a telephone exchange, a plurality of trunk circuits containing relays, a plurality of translating devices common to said trunk circuit, means for associating one of said devices with a trunk circuit, testing mechanism, and means for associating said test mechanism with the input and output circuits of said trunk circuit and for dissociating said translating device therefrom, said means cooperating with said trunk circuit relays to render the dis-associated translating device unselectable from other trunk circuits. 90
10. In a telephone exchange, a trunk circuit containing relays, a test mechanism containing relays, a plurality of switch mechanisms and an impulse recording device, means for connecting said test mechanism with the input and output circuit of said trunk circuit relays, means in the testing mechanism for impulsing either said trunk circuit or test mechanism relays, means in one instance for directing the impulses from said test mechanism relays to said switch mechanisms, and means in another instance for directing the impulses from said trunk circuit relays to either of the switches of the test mechanisms or to an impulse recording device. 105
11. In a telephone exchange, a translating device containing switch mechanisms and an impulsing device, test mechanism containing relays, a plurality of switch mechanisms and an impulse recording device, means for connecting said test mechanisms with the input and output circuits of said translating device, means in the test mechanism for impulsing said relays, means for directing the impulses from said relays to operate said switch mechanisms of either the testing mechanism or the translating device, and means for directing the impulses from said impulsing device of the translating device either to the switches of the testing mechanism or to the impulse recording device. 110
12. In a telephone exchange, a translating device having means for registering, translating and retransmitting a telephone number and means for thereafter disconnecting itself, a test mechanism containing relays, registers and a signal, means for associating said testing mechanism with the translating device, means for causing said testing mechanism relays to impulse into said translating device, means for intercepting the telephone number sent out by said translating device and registering it upon said testing mechanism registers, and means for operating said signal when said translating device disconnects itself. 115
13. In a telephone exchange, a trunk circuit, a translating device, a switch train, means for extending said trunk circuit to said translating device, means for thereafter switching through said trunk circuit to said switch train and disconnecting it from said translating device, a testing mechanism containing a signal, means for associating said testing mechanism with said trunk circuit, means in the testing mechanism for operating said switching through means, and means for flashing said signal if the switching through means operates properly. 120
14. In a telephone exchange, a trunk circuit, a switch train, a translating device, means for connecting said trunk circuit to said translating device, a device in said trunk circuit for disconnecting said translating device and switching through said trunk circuit to said switch train, means in said translating device for controlling the switching through device of the trunk circuit, testing equipment, means for connecting it to either the trunk circuit or the translating device, said testing equipment including means for operating said switch through device, means for causing said translating device to operate its switch through control means, and means for supervising said operations. 125
15. In a telephone exchange, a trunk circuit, a translating device, means for connecting the trunk circuit to the translating device, means in said trunk circuit for break- 130

ing the established connection, means in said translating device for controlling said disconnect means, testing equipment, means for connecting it to either the trunk circuit 5 or the translating device, means in said testing equipment for controlling said disconnect means of the trunk circuit, means for causing the translating device controlling means to function, and means for supervising 10 the operation of the disconnect and controlling means.

16. In a telephone system, a trunk circuit, translating equipment connected thereto, a relay for disconnecting the two, a device 15 in the translating equipment for operating said relay at a definite time, testing equipment, said testing equipment having access to both the trunk circuit and the translating equipment, means in the testing equipment for causing the operation of said relay or the operation of said device, and means 20 in the testing equipment for indicating the correct or incorrect functioning of said device or relay.

17. In a telephone system, a trunk circuit having a translating device associated therewith, that translating device having means responsive to digits of a called number transmitted from the trunk circuit for translating 30 and retransmitting said digits, testing equipment, and means for connecting it to said trunk circuit or translating device, said testing equipment having means for intercepting the impulses delivered either from the trunk circuit or from the translating device 35 and for observing or registering said impulses.

18. In a telephone system, a trunk circuit having a translating device associated therewith, said translating device having means responsive to digits of a called number transmitted from the trunk circuit for translating and retransmitting said digits, testing equipment, means for connecting it to said 45 trunk circuit or translating device, said testing equipment having means for transmitting impulses of different character to the trunk circuit or to the translating device, and having also means for intercepting the 50 impulses delivered either from the trunk

circuit or from the translating device and for observing or registering said impulses.

19. In a telephone system, a trunk circuit, a translating device associated therewith including means responsive to impulses from the trunk circuit for translating and retransmitting the digits of a called number, testing equipment including impulse transmitting devices, impulse recording devices and switch mechanism, means for connecting the testing equipment either with the trunk circuit or the translating device, and a set of keys in the testing equipment certain of which connect the transmitting devices with either the trunk circuit or the translating device and others of which connect the impulse recorder or the switch mechanism with either the trunk circuit or the translating device.

20. In a telephone exchange, a plurality of 70 trunk circuits containing relays, a plurality of translating devices, common to and selectable by said trunk circuits, means for associating one of said devices with a trunk circuit, testing mechanism, means for associating said testing mechanism with the input and output circuits of said trunk circuits, and for dis-associating said translating device therefrom, said means cooperating with said trunk circuit relays to render said dis-associated translating device unselectable by other trunk circuits, means in said test mechanism for transmitting impulses to the relays of said trunk circuit under varying conditions, and means in the test mechanism responsive to impulses transmitted by said 80 trunk circuit relays.

21. In a telephone exchange, a plurality of trunk circuits containing relays, a test mechanism containing a plurality of devices each 90 adjusted to operate on different types of impulses, means for associating said test mechanism with said trunk circuit relays and for impulsive said relays, and means for directing the impulses delivered by said relays to 95 operate said devices.

In witness whereof, I hereunto subscribe my name this 4th day of Oct., A. D., 1924.

FRED T. MADSEN.
